UNITED STATES PATENT OFFICE.

NICHOLAS S. VEDDER AND FRANCIS RITCHIE, OF TROY, NEW YORK, AS
SIGNORS TO SWETT, QUIMBY, & PERRY, OF SAME PLACE.

DESIGN FOR BASE-BURNING STOVES.

Specification forming part of Design No. 7,775, dated September 22, 1874; application filed August 22, 1874.
[Term of Patent 7 years.]

To all whom it may concern:

Be it known that we, NICHOLAS S. VEDDER and FRANCIS RITCHIE, each of the city of Troy, in the county of Rensselaer and State of New York, have jointly invented and produced a new and original ornamental Design for Base-Burning Stoves, of which the following is a specification, reference being had to the accompanying photograph of a stove, which embodies our said new design.

One part of our invention consists of the design for the urn A, composed of the foot and stem z, shaped as shown, the handles y y, of the form represented, and the cylindrical body x, having the band of quadrangular ornaments w, arranged point to point about its middle, and the ornamental moldings v u around its top and bottom, and all shaped and disposed together so as to appear substantially as represented in the accompanying photograph.

Another part of our invention consists of the design for the circular removable cover B, composed of the uppermost ornamental concave section or molding t, the next adjacent ornamental concave molding or section s, the ornamental convex section r, and the lowermost smooth convex section q, all of the sections being annular, with ledges between them, and all shaped and disposed so as to appear as represented in the aforesaid photograph.

Another part of our invention is the design for the annular top-supporting plate D, as distinguished by its upwardly-flaring form, and having around its upper part the row of downwardly-pointed ornaments m, and around its lower part the row of downwardly-pointed ornaments l, having their broad upper portions connected together by short bars with beads, and each partly covered by a disk round on the lower edges, and having a little central knob, all as seen, by sharp inspection, in the aforesaid photograph.

Another part of our invention consists of the design for the ornamental panel-borders F, composed of the two pairs of opposite arches k and j, each formed of the middle, flat, plain, part, the outer raised edge-molding, and the inner edge-molding having a row of semicircular ornaments along its outer edge, and scroll-like inner ends united by an intervening ornament, all shaped and disposed as shown in the aforesaid photograph.

Another part of our invention consists of

the design for panel-ornaments, composed of the ornamental inner surface E and ornamental border F, each composed and all shaped and disposed together, as shown in the accompanying representation.

Another part of our invention is the design for the rectangular panels G, composed of the middle ornamented surface E, compound ornamental border F, horizontally-grooved corner surfaces i, and outer moldings h, with or without the rosettes g, all shaped and arranged together so as to appear substantially as represented in the aforesaid photograph.

Another part of our invention is the design for the upper cylindrical section H, consisting of three or more of the panels G, composed as above specified, and arranged together with interviewing rows of diamond-shaped ornaments f, all so as to appear as represented in the photograph aforesaid.

Another part of our invention is the design for the upper mica light-doors I, each consisting of three mica-spaces having the bottom bar e, side bars e', and Gothic arched top e'', ornamented as shown, and the cap-piece d, composed of straight and curved moldings and scroll-like ornamentations, all as shown in the photograph.

Another part of our invention is the design for the upper mica light-section J, consisting of segments curved as shown, with division-strips c, of diamond-shaped projections, and raised ornamentations c' on the upper parts, all shaped and disposed as shown in the aforesaid representation.

Another part of our invention is the design for the fire-pot section K, consisting of segments divided by the diamond-shaped ornamentations b, and having the row of ornamentations b' along the upper part, and the series of compound ornaments b'' along the lower part, all shaped and disposed as represented in the aforesaid photograph.

Another part of this invention is the design for the lower mica light-doors L, each consisting of the two mica-spaces a, the middle bar a', the bottom and side pieces a'', and the cap-piece a''', all shaped and arranged together as shown in the photograph aforesaid.

Another part of our invention is the design for the lower mica light-section M, consisting of inclined segments f', with division-strips d', of diamond-shaped ornaments, and the orna-

mented border-moldings *k'*, all shaped and disposed as shown in the aforesaid photograph.

Another part of this invention is the design for the ash-pit draft-door *N*, consisting of the ornamental surface *E* in a rectangular panel, having the border-molding *g'* and the projecting oblong rectangular damper-case *h'*, having oblong upright apertures with arched tops and intervening rows of ornamentations within a border-molding, the whole being shaped and arranged together as shown in the accompanying representation.

Another part of our invention is the design for the sides *O* of the ash-pit section, consisting of the ornamental sub-panel *E F*, the grooved surfaces *i*, the moldings *h*, and the horizontally-grooved upright projecting portions *i'*, all shaped and arranged together as represented in the photograph.

Another part of our invention is the design for the base-plate *P*, as distinguished by the particular form, in plan and in profile combined, of the outer border-molding *Q* and the inner border-molding *R*, in connection with the ornamentations thereon, as shown in the aforesaid photograph.

Another part of our invention is the design for the leg *S*, as distinguished by the shell-like center or knee-piece *t'*, the horizontally-grooved surfaces *u'*, the ornamental scroll sides *v'*, and the foot *w'*, all shaped and disposed as shown in the photograph aforesaid.

What we claim as new, and of our invention, is—

1. The design for the urn *A*, composed of the foot and stem *z*, handles *y y*, and body *x*, having the row of ornaments *w* and ornamental moldings *v u*, all shaped and disposed together as herein specified, and represented in the accompanying photograph.

2. The design for the circular cover *B*, composed of the ornamental annular concave moldings *t* and *s*, the ornamented convex molding *r*, and the plain convex molding *q*, all shaped and arranged together as shown and described.

3. The design for the annular plate *D*, as distinguished by the rows of ornaments *m* and *l*, shaped and arranged together as herein specified, and shown in the aforesaid photograph.

4. The design for the ornamental panel-border *F*, composed of the two pairs of opposite arcs, *k* and *j*, formed of the particular parts, moldings, and ornaments herein specified, and shown in the photographic representation.

5. The design for the compound panel ornament, consisting of the ornamental surface *E* and ornamental moldings or border *F*, formed and combined as shown and described.

6. The design for the rectangular panels *G*, composed of the surface *E*, border *F*, grooved surfaces *i*, and moldings *h*, all shaped and arranged together as shown and specified.

7. The design for the upper cylindrical section *H*, consisting of the panels *G*, formed as specified, and the intervening rows of ornaments *f*, as shown and described.

8. The design for the upper mica light-doors *I*, composed of three apertures, with the bottom bars *e*, side bars *e'*, Gothic arch-top *e''*, and cap-piece *d*, all shaped, ornamented, and arranged together as described and shown.

9. The design for the upper illuminating-section *J*, composed of sections divided by the rows of diamond-shaped ornamentations *c*, with the ornamentations *c'* on the upper parts, all shaped as shown and specified.

10. The design for the fire-pot section *K*, as divided into segments by the ornamental strips *b*, with the ornamentation *b'* along the upper part, and the series of compound ornaments *b''* upon the lower part, all shaped and arranged as specified and shown.

11. The design for the lower mica light-doors *L*, as distinguished by the two apertures *a a* in each door, middle bar *a'*, bottom and side pieces *a''*, and cap-piece *a'''*, all shaped, ornamented, and arranged as shown.

12. The design for the lower illuminating-section *M*, consisting of the segments *f'*, connected by the ornamental strips *d'*, and having the ornamented border-moldings *k'*, all as shown and described.

13. The design for the ash-pit door *N*, as distinguished by the ornamental surface *E*, in a rectangular panel having the border-molding *g'*, and the projecting oblong damper-case *h'* having oblong upright draft-apertures, with round arched tops and intervening rows of ornamentations within an outside border-molding, all shaped and arranged together, as shown.

14. The design for the sides *O* of the ash-pit section, consisting of the ornamental sub-panel *E F*, grooved surfaces *i*, moldings *h*, and the horizontally-grooved projections *i'*, all as shown and described.

15. The design for the base-plate *P*, as distinguished by the particular forms, in plan and profile, of the outer border-molding *Q* and inner border-molding *R*, and the ornamentations thereon, all as shown in the accompanying photographic representation.

16. The design for the leg *S*, as distinguished by the shell-like knee-piece *t'*, horizontally-grooved surfaces *u'*, ornamental side scrolls *v'*, and foot *w'*, all shaped and arranged together, as represented in the accompanying photograph.

In testimony whereof we hereunto subscribe our names.

NICHOLAS S. VEDDER.
FRANCIS RITCHIE.
